UNITED STATES PATENT OFFICE.

ELMER ELLSWORTH McCANNON, OF BARNHART'S MILLS, PENNSYLVANIA.

GLOBE-VALVE.

SPECIFICATION forming part of Letters Patent No. 292,340, dated January 22, 1884.

Application filed September 24, 1883. (No model.)

To all whom it may concern:

Be it known that I, ELMER E. McCANNON, a citizen of the United States of America, residing at Barnhart's Mills, in the county of 5 Butler and State of Pennsylvania, have invented certain new and useful Improvements in Globe-Valves; and I do hereby declare the following to be a full, clear, and exact description of the invention, such as will enable others skilled in the art to which it appertains to 10 make and use the same, reference being had to the accompanying drawings, and to letters or figures of reference marked thereon, which form a part of this specification.

15 This invention relates to certain new and useful improvements in globe-valves, its object being to improve on the construction of the ordinary globe-valve, so as to provide a means which will prevent the valve from getting off 20 its seat; also, to do away with a rotary or axial motion of the valve, so that the valve will be pressed upon its seat by a direct vertical motion.

25 My invention consists in providing the valve with guideways, and in the construction and combination of the parts, as will be hereinafter fully set forth, and illustrated in the accompanying drawings.

30 In the drawings, Figure 1 is a side elevation of my improved valve, with one-half in section. Fig. 2 is a sectional view taken through the line $x-x$ of Fig. 1. Fig. 3 is a vertical section taken through the line $y-y$ of Fig. 2; and Figs. 4 and 5 are detailed views, partly in sections.

35 In the drawings, A represents the shell or case of a valve, which is provided with the usual end openings, $a-a$, which are provided with internal screw-threads and an upper opening, a' , which is also internally screw-threaded, these openings being common to this class of valves. 40 The shell is also provided with a central horizontal valve-seat, B, from one side of which there is an upwardly-projecting wall, b , and on the opposite side a downwardly-projecting wall, b' .

45 It will be readily seen that the foregoing parts of my valve are of ordinary construction, and may be manufactured in the usual manner.

The shell of this valve is provided on its position above the valve-seat with two vertical

guides, C C, which are cast upon the shell and 50 extend from the edge of the valve-seat upwardly to the upper screw-threaded portion of the shell. The edges of these guides C C are parallel with each other, and they are formed integral with the shell. These guides are fully 55 illustrated in Figs. 2 and 3 of the accompanying drawings.

D represents the stem or screw-spindle, which is used for operating the valve by turning the same, though when this spindle is turned it 60 does not raise or lower itself, but converts the rotary movement which is imparted to it by the handle into a vertical movement of the valve. This stem or spindle D is provided at its lower end with a screw-threaded portion, 65 D', above which is formed a shoulder, D².

E represents the cap or cover of the shell, which is screw-threaded, as shown at e, so as to be secured to the shell or case, and it is provided on its lower portion with internal 70 screw-threads, e', in which is placed a screw-threaded nut, E', having an external screw-threaded portion and a smooth cylindrical opening through the same. The upper end of the nut rests or bears against the shoulder D², 75 formed on the stem, and will hold the same in position against vertical displacement. The upper portion of the cap or cover E is provided with a screw-bushing of ordinary construction.

The stem D is first placed in the cap E and 80 the nut E' passed over the screw-threaded portion D' of the stem and turned home. The upper end of this nut bears upon the under side of the shoulder D², and prevents the stem from moving downwardly. The conical portion of 85 the box E will prevent an upward movement of the stem, as the conical portion of the stem bears against the same. After the stem is secured in position, the operating-wheel at the upper end of the same may be secured in position by a suitable key. The screw-threaded portion of the nut E' is of sufficient length, so that the parts may be tightened to take up any 90 wear of the shoulder D² or end of the nut E'.

The valve F is provided on its under side 95 with an inclined or tapering edge, f, which will fit snugly upon the valve-seat, and it is provided on its under side with a central hol-

low portion, F', also with a transverse slot, G, for the reception of a guide-plate, H. This valve is screw-threaded interiorly at the portion shown at f', for the reception of the screw 5 D' upon the lower end of the stem.

The guide-plate H, hereinbefore referred to, has a central circular opening, h, of larger diameter than the lower end of the screw-threaded portion of the stem, and the upper end of 10 the valve is provided with an opening of the same diameter. The guide-plate H is of sufficient length to extend beyond the periphery of the valve, and it is provided with notches h', which extend inwardly to about the edges of 15 the valve-seat.

It will be seen from the construction hereinbefore described and illustrated that this valve may be readily turned true without the employment of specially skilled labor.

20 When it is desired to place the parts of the valve together, the guide-plate H is slipped into the slot G in the valve, and said valve placed within the valve-seat, the notches h' in the end of the guide-plate embracing the guides 25 C C, formed within the shell. The cap E is then screwed in place, and the stem being turned enters the screw-threaded socket in the portion F' of the valve, the parts thus being organized as shown in the accompanying drawings.

30 The valve F, it will be seen by this construction, is moved in a vertical direction when the stem is turned, and the guide-plate H will hold said valve so that it cannot be displaced, 35 and will prevent a rotary or axial motion of the same.

It will also be noticed that in the construction of this valve no packing is required, and both the upper and lower ends of the stem are braced against a rocking motion, and as there 40 is no rotary motion of the valve there is but little wear; also, there are no joints other than the valve and valve-seat that need to be ground.

Having thus described my invention, what I claim as new, and desire to secure by Letters 45 Patent, is—

1. The shell A, having outlet and inlet openings, and guides C C, located above the valve-seat, in combination with a screw-spindle attached to the shell, and a valve, F, provided 50 with a transverse slot, in which is placed a guide-plate, H, which is recessed at its ends, so as to embrace the guides C C, substantially as shown, and for the purpose set forth.

2. The shell A, having a central valve-seat, 55 and side guides, C C, formed thereon, and means for holding the stem, said stem being provided with a screw-threaded end, in combination with a valve, F, having a screw-threaded portion, f', and transverse slot G, for the reception 60 of a guide-plate, H, with recessed end, the parts being organized substantially as shown, and for the purpose set forth.

In testimony whereof I affix my signature in presence of two witnesses.

ELMER ELLSWORTH MCCANNON.
